G. W. WILLIAMS

RAILWAY TIE SHIFTER

Filed Oct. 11, 1923

Witnesses:

G. W. Williams.

Attorney

UNITED STATES PATENT OFFICE.

GEORGE W. WILLIAMS, OF ELM CITY, NORTH CAROLINA.

RAILWAY-TIE SHIFTER.

Application filed October 11, 1923. Serial No. 667,875.

To all whom it may concern:

Be it known that I, GEORGE W. WILLIAMS, citizen of the United States, residing at Elm City, in the county of Wilson and State of North Carolina, have invented certain new and useful Improvements in Railway-Tie Shifters, of which the following is a specification.

This invention relates to certain new and useful improvements in railway tie shifting devices and has particular reference to a rail clamp adapted to form an abutment for a jack employed in shifting railway ties longitudinally of the rails to their proper position.

The primary object of the invention is to provide a railway clamp of the above kind which embraces the desired qualities of simplicity, durability, and efficiency in operation.

Another object is to provide a rail clamp of the above kind which has jaw members so formed and related as to effectively prevent slipping of the clamp longitudinally of the rail and to prevent downward tilting or displacement of the clamp bodily upwardly relative to or from the rail, accidentally, while permitting ready removal of the clamp from the rail when manually tilted upwardly.

Another object is to generally simplify and improve rail clamps of the above kind, whereby the same may meet with all of the requirements for a successful commercial use.

Other objects will appear as the nature of the invention is better understood, and the same consists in the novel form, combination and arrangement of parts hereinafter more fully described, shown in the accompanying drawings, and claimed.

In the drawing, wherein like reference characters indicate corresponding parts throughout the views:

Figure 1 is a fragmentary top plan view illustrating a tie shifting device embodying a rail clamp constructed in accordance with the present invention and operatively related with a rail and tie.

Figure 2 is a side elevational view of the rail clamp shown in Figure 1, drawn on a larger scale and shown operatively engaged with the rail, and

Figure 3 is a view similar to Figure 2, 55 showing the clamp as it appears partially

engaged with the rail to illustrate the manner of applying the clamp.

In the form of the invention shown in the drawings, the clamp embodies a single sheet of suitable material such as steel, formed to provide a body portion 5 having relatively shallow rectangular socket 6 in opposite sides thereof and provided upon one end with integral jaws 7 and 8, the angular jaw 7 being of angular form so as to extend across the ball of the rail 9 as shown in Figure 2, and to depend at the farther side of the ball of the rail when applied.

The inner jaw 8 projects downwardly and inwardly below the outer jaw 7, and the upper portion of the face of the jaw 8 which is opposed to the face of the depending portion of the jaw 7 conform to and lie closely adjacent opposite sides of the ball of the rail 9 when the clamp is applied as is also shown in Figure 2, wherein the inner surface of the upper horizontal portion of the jaw 7 is disposed upon the top of the bar of the rail.

The lower end of the depending arm of the outer jaw 7 is provided with a transversely extending arcuate recess 10 in which the adjacent lower corner portions of the ball of the rail may engage when the clamp is tilted upwardly as shown in Figure 3, for thus forming a fulcrum about which the clamp is tilted. The projecting lower portion of the inner jaw 8 has its inner face curved or of arcuate form as at 11, and the center of curvature of the face 11 is at the fulcrum point furnished by the arcuate recess 10.

In applying the clamp to the rail 9, the jaw 7 is engaged with the ball of the rail so that a lower corner of the ball of the rail is seated within the recess 10 as shown in Figure 3. The clamp is then tilted downwardly in the direction of the arrow "a" as is permitted by the arcuate face 11 forming a clearance for the opposite side of the ball of the rail, and then the clamp is shifted slightly in a horizontal direction or transversely of the rail to bring the lower end of the jaw 8 into contact with the web of the rail as shown in Figure 2. When thus disposed, the lower end of the depending arm of the jaw 7 is disposed beneath one side of the ball of the rail and the upper end of the inwardly projecting lower portion of the jaw 8 is disposed beneath the 110

other side of the ball of the rail so that accidental displacement of the clamp from the rail bodily in a vertical direction or upwardly is prevented. The engagement of 5 the lower end of the jaw 8 with the web of the rail limits the downward tilting movement of the clamp onto the rail to a position wherein the body 5 extends outwardly horizontally in proper position to 10 be engaged by the head of a jack as shown in Figure 1.

In use, the clamp is applied to the rail as above described and as shown in Figure 1, at one side of the tie 12 to be shifted. 15 Any suitable form of jack 13 is then placed between adjacent sides of the clamp and the tie 12 with the base of the jack engaging the tie as at 14 and with the head 15 of the jack engaged in the socket 6 in the adjacent side of the body portion 5 of the clamp. When the jack is operated in the proper manner to extend the same, the clamp is slightly canted so as to dig into the sides of the rail with a gripping 25 engagement that is increased in proportion to the increase in pressure exerted against the clamp by the jack. Thus, as the clamp cannot move longitudinally of the rail, the tie 12 will be forced away 30 from the clamp or shifted to its proper position. By providing a socket 6 in each side of the body portion 5, the clamp may be utilized upon either rail of a track, or the jack may be utilized at either side of 35 the clamp. In removing the clamp, the same is merely tilted upwardly from the position of Figure 2, to a position slightly further upwardly than shown in Figure 3, whereupon the jaws are so related to 40 the ball of the rail as to permit the clamp's ready removal.

From the foregoing description, it is believed that the construction and operation as well as the advantages of the present 45 invention will be readily understood and appreciated by those skilled in the art.

Minor changes may be made without departing from the spirit and scope of the invention as claimed.

What I claim as new is:

1. In a railway tie shifting device, a rail clamp including a body member having rigid inner and outer jaws upon one end thereof and adapted to form an abutment for a jack, the outer jaw being of angular form so as to extend across the top and extend downwardly along one side of the ball of the rail, the downwardly extending portion of said outer jaw being provided with an arcuate recess in the lower portion thereof adapted to engage adjacent lower corner portions of the ball of the rail to provide a fulcrum about which the clamp may be bodily tilted in applying or 60 removing the latter, said inner jaw depend-

ing below and extending inwardly toward the outer jaw and having the inner face of the lower portion thereof of arcuate form with its center of curvature at said fulcrum. 70

2. In a railway tie shifting device, a rail clamp including a body member having rigid inner and outer jaws upon one end thereof and adapted to form an abutment for a jack, the outer jaw being of angular form so as to extend across the top and extend downwardly along one side of the ball of the rail, the downwardly extending portion of said outer jaw being provided with an arcuate recess in the lower portion thereof adapted to engage the adjacent lower corner portion of the ball of the rail to provide a fulcrum about which the clamp may be bodily tilted in applying or removing the latter, said inner jaw depending below and extending inwardly toward the outer jaw and having the inner face of the lower portion thereof of arcuate form with its center of curvature at said fulcrum, said inwardly extending lower end portion of the inner jaw being arranged to engage the adjacent side of the web of a rail when the clamp is operatively applied to the latter for limiting downward tilting movement of the clamp at a point wherein the body portion is horizontally disposed at one side of the rail in proper position to act as an abutment for a jack. 80 85 90 95

3. In a railway tie shifting device, a rail clamp including a body member having rigid inner and outer jaws upon one end thereof and adapted to form an abutment for a jack, the outer jaw being of angular form so as to extend across the top and extend downwardly along one side of the ball of the rail, the downwardly extending portion of said outer jaw being provided with an arcuate recess in the lower portion thereof adapted to engage adjacent lower corner portions of the ball of the rail to provide a fulcrum about which the clamp may be bodily tilted in applying or removing the latter, said inner jaw depending below and extending inwardly toward the outer jaw and having the inner face of the lower portion thereof of arcuate form with its center of curvature at said fulcrum, the portion of the outer jaw below the arcuate recess thereof and the upper end of the lower portion of the inner jaw providing shoulders positioned beneath opposite sides of the ball of the rail when the clamp is completely applied to the latter, whereby direct upward displacement of the clamp from the rail is prevented. 100 105 110 115 120 125

4. In a railway tie shifting device, a rail clamp including a body member having rigid inner and outer jaws upon one end thereof and adapted to form an abutment for a jack, the outer jaw being of angular 130

form so as to extend across the top and extend downwardly along one side of the ball of the rail, the downwardly extending portion of said outer jaw being provided with 5 an arcuate recess in the lower portion thereof adapted to engage adjacent lower corner portions of the ball of the rail to provide a fulcrum about which the clamp may be bodily tilted in applying or removing the 10 latter, said inner jaw depending below and

extending inwardly toward the outer jaw and having the inner face of the lower portion thereof of arcuate form with its center of curvature at said fulcrum, said body portion having sockets in opposite sides thereof 15 for seating reception of the head of the jack.

In testimony whereof I affix my signature.

GEO. W. WILLIAMS.
